BATHTUB

John F. Eyring, Baltimore, Md.

Application May 10, 1951, Serial No. 225,656

9 Claims. (Cl. 4—181)

1

This invention relates to certain improvements in bathing apparatus with particular reference to a novel construction of bath tub and the like, whereby obvious objections to tub bathing are eliminated and the tub can be maintained in a clean and sanitary condition at all times.

The object of the invention is the production of a bath tub having means to perform various types of bathing, such as a tub and shower bath, and during either or both operations maintaining the water in the tub in a clean and sanitary condition.

Another object of the invention is to provide a tub whereby that portion adjacent the upper surrounding edge thereof has integrally formed therewith adjacent parallel conduits or passageways adapted to receive water from a controlled source to selectively direct said water into the proper conduits or passageways according to the type of bath and operational function desired.

A further object is to provide a device of the type indicated that will be practical, both from the standpoint of construction and use, and one that can be manufactured by conventional methods with little or no additional cost.

A still further object is the production of a tub construction provided with an overflow gutter extending substantially around the whole upper part of the tub at a height to receive and carry off all of the soiled or unclean water from the surface of the water in the tub during a bathing period, means being provided to maintain a regulated, constant flow of water into said tub during the entire bathing operation.

It is a further object to use this gutter as a flush rim or means for washing down the sides of the tub after a bath, means being provided for directing clean water into said gutter for this purpose after the tub has been drained through the conventional drain in the bottom of the tub. This flushing water will also maintain the gutter in a clean and sanitary condition, said gutter at the low end being provided with a drain opening for removing any sediment or soiled water not flushed over the edge of said gutter. It is of course to be understood that this gutter drain is also functioning while the gutter is receiving the overflow from the tub during the bathing operation.

A still further object of the invention is to combine with the other features hereinbefore mentioned, a rim shower so that the bather may, if desired, by manipulating the proper valve, obtain a rinse or washdown after his tub bath.

The preferred embodiment of the invention is

2

illustrated in the accompanying drawings in which:

Figure 1 is a top plan view of the improved tub.

Figure 2 is a longitudinal vertical sectional view thereof.

Figure 3 is a transverse sectional view on line 3—3 of Figure 1.

Figure 4 is a transverse vertical sectional view on line 4—4 of Figure 1.

Figure 5 is an enlarged partial vertical sectional view on line 5—5 of Figure 1, showing in detail the supplemental water discharge chamber and the adjoining ends of the overflow gutter and its parallel flushing conduit, together with the water supply piping therefor.

Figure 6 is an enlarged detail sectional view on line 6—6 of Figure 1, showing a transverse section of said water discharge chamber.

Figure 7 is an enlarged detail transverse sectional view on line 7—7 of Figure 1 more clearly showing the various passageways comprising the overflow gutter, the water supply conduit for flushing said gutter, and the shower spray conduit, all formed as an integral casting with the tub; and

Figure 8 is a perspective view of one end of the tub more clearly showing the relationship of the various parts of the tub proper.

Referring to the drawings in detail, and with particular reference to Figures 2, 7 and 8, the improved tub 1 is preferably made as a casting having formed integrally with the upper surrounding rim portion, adjacent parallel passageways or conduits consisting of a gutter 2, a water supply conduit 3 for flushing said gutter, and a water supply conduit 4 for the shower spray.

The gutter 2 is provided with a drain connection 5 and the tub is provided with the usual bottom drain 6. The main water supply for filling the tub 1 is the usual mixing faucet 7.

The gutter 2 and the water conduits 3 and 4 extend completely around the tub except at one end where there is interposed a supplemental water discharge chamber 8 (see particularly Figs. 4, 5 and 8), the lower edge of said chamber 8 being on the same level or horizontal plane with the upper edge of the overflow rim 9 of the gutter 2.

For the purpose of flushing the gutter 2 for cleaning purposes, the conduit 3 is provided with spaced bottom openings 10 extending around the tub, the complete length of said conduit 3.

Formed in the inner side wall of the conduit 4 are inwardly directed spaced openings 11 also extending around the upper edge of the tub 1,

providing a shower spray as desired when water is supplied to said channel 4.

These various passageways, conduits, chambers and the like, may be supplied with water in any conventional manner provided the water supply is selectively controlled according to the operation or function desired.

One form of piping is illustrated in Figure 5 wherein a main hot and cold water pipe 12 is provided with branch pipes 13 and 14 for furnishing water to the supplemental water discharge chamber 8 and to each opposite end of the gutter 2 respectively, whereby during the continuous supply of water to the chamber 8 a certain amount of water will be simultaneously directed into the gutter 2 to provide a movement or circulation of water along the gutter to the gutter drain 5 as the water in the tub overflows into said gutter during a tub bath, in a manner and for the purpose to be hereinafter more fully described.

This supply pipe 12 may be provided with a conventional mixing valve (not shown) to obtain proper water temperature for the bath.

The flushdown conduit 3 is supplied with water through a pipe 15 and the shower spray conduit 4 is supplied through a pipe 16, said pipes 15 and 16 being provided with the necessary control valves (not shown), whereby all of the water supply pipes 12, 15 and 16 will be capable of selective control, either singularly or in combination according to the type of bath desired and the proper function to be performed.

In using the tub, the same is filled through the usual faucet 7 until the water level has reached the top of the overflow rim 9 of the gutter 2, whereupon this faucet is closed and a limited amount of water is continuously supplied to the tub through the supplemental water discharge chamber 8 by way of pipes 12 and 13, just sufficient to maintain a steady overflow of the soiled surface water into the gutter 2 during the bath, where it is carried along and discharged to the waste through the drain 5.

At the same time water is being admitted to the chamber 8, a relatively smaller amount of water is admitted into the opposite ends of the gutter 2 by way of pipes 14 for the purpose of creating a circulation of the overflow water towards the gutter drain 5.

After the tub bath, the water supply through the pipes 13 and 14 is shut off and the tub drained through the main drain 6.

If a washdown shower is now desired to complete the bath, water is admitted through pipe 16 into the channel 4 and out through the spray openings 11.

The final operation, after shutting off the water to the spray shower pipe 16, is a flushing of the gutter 2 and a washdown of the sides of the tub which is accomplished by opening the valve to water pipe 15, whereby the water will be directed into the gutter through the top openings 10 for flushing the same and will flow down the sides of the tub in an obvious manner and carry all dirt and sediment out through the gutter drain 5 and the main drain 6.

It is to be understood that applicant is not to be limited to the specific features as shown and described herein, as slight changes may be made without departing from the spirit of the invention as covered in the appended claims.

What I claim is:

1. A bath tub having adjoining parallel passageways extending around the upper edge

thereof and a supplemental water supply chamber for said tub, said passageways extending from each side of said water supply chamber but separated therefrom and comprising an overflow gutter, a water supply conduit for flushing said gutter and a water supply conduit provided with shower spray openings, and valve controlled means for supplying water to said supply chamber, conduits and passageways.

10 2. A bath tub having a main water supply for initially filling said tub, adjoining parallel passageways extending around the upper edge thereof, and a supplemental water supply chamber for continuously supplying a regulated amount of water to said tub, said passageways extending from each side of said water supply chamber but separated therefrom and comprising an overflow gutter, a water supply conduit for flushing said gutter and a water supply conduit provided with shower spray openings, and valve controlled means for supplying water to said supply chamber, conduits and passageways.

15 3. A bath tub having at one end an open sided water discharge chamber for supplying water to said tub, parallel passageways extending around the upper edge of said tub, said passageways extending from each side of said water supply chamber but separated therefrom and comprising an open sided overflow and flushdown gutter for said tub, a water supply conduit provided with shower spray openings, and valve controlled means for selectively supplying water to said discharge chamber, conduit and said overflow and flushdown gutter.

20 4. A bath tub having integrally formed therewith an open sided water discharge chamber for supplying water to said tub, adjoining parallel passageways extending around the upper edge of said tub, said passageways extending from each side of said water supply chamber but separated therefrom and comprising an open sided overflow and flushdown gutter for said tub, a water supply conduit for said gutter, and a water supply conduit provided with shower spray openings, and valve controlled means for selectively supplying water to said discharge chamber, conduits and passageways.

25 5. A bath tub having integrally formed therewith an open sided water discharge chamber for supplying water to said tub, integrally formed adjoining parallel passageways extending around the upper edge of said tub, said passageways extending from each side of said water supply chamber but separated therefrom and comprising an open sided overflow and flushdown gutter for said tub, a drain for said gutter, a water supply conduit for said gutter and a water supply conduit provided with shower spray openings, and valve controlled means for selectively supplying water to said discharge chamber, conduits and passageways.

30 6. A bath tub having integrally formed therewith an open sided water discharge chamber for supplying water to said tub, integrally formed adjoining parallel passageways extending around the upper edge of said tub from each side of said water discharge chamber and at substantially the same level, said passageways extending from each side of said water supply chamber but separated therefrom and comprising an open sided overflow and flushdown gutter for said tub, a drain for said gutter, a water supply conduit for said gutter and a water supply conduit provided with shower spray openings, and valve controlled

means for selectively supplying water to said discharge chamber, conduits and passageways.

7. A bath tub having integrally formed therewith an open sided water discharge chamber for continuously supplying water to said tub, parallel passageways extending around the upper edge of said tub from each side of said water discharge chamber, said passageways extending from each side of said water supply chamber but separated therefrom and comprising an open sided overflow and flushdown gutter for said tub, a water supply conduit for said gutter and a water supply conduit provided with shower spray openings, and valve controlled means for selectively supplying water to said discharge chamber, conduits and passageways.

8. A bath tub having integrally formed therewith an open sided water discharge chamber for continuously supplying water to said tub, parallel passageways extending around the upper edge of said tub from each side of said water discharge chamber, said passageways extending from each side of said water supply chamber but separated therefrom and comprising an open sided overflow gutter for carrying off soiled surface water from said tub and for subsequently washing down the sides of said tub, a drain for said gutter, a water supply conduit for flushing said gutter, and a water supply conduit provided with openings for producing a shower spray, and valves for selectively controlling the water to either the tub, the gutter or shower spray or any combination thereof, according to the operation desired.

9. A bath tub having integrally formed there-

with an open sided supplemental water discharge chamber for continuously supplying water to said tub, a main water supply for initially filling said tub, a main drain for said tub, adjoining parallel passageways extending around the upper edge of said tub from each side of said water discharge chamber and at substantially the same level integrally formed with said tub, said passageways extending from each side of said water supply chamber but separated therefrom and comprising an open sided overflow gutter, for carrying off soiled surface water from said tub and for subsequently washing down the sides of said tub, a drain for said gutter, a water supply conduit for flushing said gutter and the sides of said tub, and a water supply conduit provided with openings for producing a shower spray, and hot and cold water valves for selectively controlling said water to either the tub, the gutter or shower spray or any combination thereof, according to the operation desired.
